FIVE-ROLL CEMENTING MACHINE

Walter P. Osgood, Malden, Mass.

Application October 18, 1934, Serial No. 748,808

20 Claims. (Cl. 12—30)

The present invention relates to cementing machines which are used in many industries and have a wide use in the manufacture of shoes in applying coating material to one face of various forms of shoe parts.

The machine which the present invention improves is able to coat with latex both the planiform and non-planiform portions on the flesh face of a shanked-out sole during its single passage through the machine. A characteristic feature of this machine is the second coating roll provided with a yielding peripheral surface constructed of rubber. This roll has to be removed frequently because there is an affinity between the latex and the rubber surfaced roll which causes the latex to build up irregularly thereon.

One of the principal objects of the present invention is to improve the machine hereinbefore referred to by providing it with a roll having a yielding peripheral surface constructed of synthetic rubber having characteristics such as to obviate the building up of the latex thereon.

To the accomplishment of this object, and such others as may appear hereinafter, the various features of the present invention reside in certain devices, constructions and arrangements of parts hereinafter described and then set forth broadly and in detail in the appended claims which possess advantages readily apparent to those skilled in the art.

The various features of the present invention will be understood readily from an inspection of the accompanying drawings illustrating the best form of the invention at present devised, in which,

Figure 1 is a view in plan of the sole cementing machine;

Fig. 2 is a view in plan, the pivoted arm carrying the upper rolls having been swung out of operating position to expose the lower rolls;

Fig. 3 is a view in plan similar to Fig. 2, the lower rolls having been removed from the coating trough, the pivoted arm having been cut away to expose the largest one of the upper rolls, and the pivoted splash guard being tipped up to show the underlying doctor;

Fig. 4 is a view in left side elevation;

Fig. 5 is a view in sectional elevation of the lower roll which engages the trailing edge of the sole last;

Fig. 6 is a view in sectional elevation on the line 6—6, Fig. 1;

Fig. 7 is a detail view in sectional elevation on the line 7—7, Fig. 1;

Fig. 8 is a detail view in sectional elevation substantially on the line 8—8, Fig. 2;

Fig. 9 is an enlarged view in sectional elevation of the doctor and splash guard mounted between the lower rolls, on the line 9—9, Fig. 2;

Fig. 10 is a detail view in left side elevation showing the coating of the skived and unskived portions of a face of a sole; and

Fig. 11 is a view in sectional elevation showing the bending of the sole during its passage through the machine and the positioning of the upper roll nearer to one of the lower rolls than to the other.

In the illustrated embodiment of the invention the coating material, preferably latex, is contained in a trough 10 (Figs. 2, 3 and 6) integral with a frame 11 (Figs. 4 and 6) secured to a base 12. The trough 10 is open at the top (Figs. 2 and 3), and is formed between the side walls 13 and 14 (Fig. 3), front wall 15 (Fig. 6), and back wall 16 of the frame. The coating material is supplied to the trough 10 by a flexible conduit 17 (Fig. 6), one end of which is connected to a T 18 secured by a nipple 19 to the bottom of the trough 10. The other end of the conduit 17 is connected to an outlet 20 (Figs. 1, 2 and 3) formed in the bottom of a receptacle 21. The bottom of the receptacle 21 is provided with interior lugs 22 which support an inverted bottle (not shown) containing coating material so that the trough 10 is supplied with the material in a siphonic or barometric manner.

The receptacle 21 is provided with an integral depending rib 23 (Figs. 4 and 6) which is pivoted intermediate its ends to one end of an arm 24 the other end of which is secured to one end of a rock-shaft 25 journaled in the side walls 13 and 14. The other end of the rock-shaft 25 carries an arm 26 (Fig. 4) provided at one end with an operating handle 27. When the machine is in use the receptacle 21 is elevated into the position of Figs. 4 and 6 by rocking the handle 27 downwardly to allow the coating material to flow from the receptacle into the trough 10. In order to maintain the receptacle 21 elevated, the arm 26 is provided with an arcuate slot 28 (Fig. 4) which embraces loosely the shank of a threaded bolt 29 projecting outwardly from the side wall 14. A hand wheel 30 threaded on the bolt 29 serves to clamp the arm 26 in any position of adjustment, there being a washer 31 interposed between the hand wheel 30 and the arm 26. When use of the machine is interrupted, the hand wheel 30 is loosened and the receptacle 21 is lowered into a position below the level of the bottom of

the trough 10 in order that the coating material therein may drain back into the receptacle.

As will be seen in Figs. 4 and 6, the lower end of the rib 23 is pivotally connected to one end 5 of a link 32 the other end of which (Fig. 6) is pivoted from the side wall 13 of the frame. This construction, together with the arm 24, rock-shaft 25, arm 26, and pivot points, provides a four-bar linkage lever which insures that the receptacle 21 will always be level whether in lowered or raised position. To facilitate draining both the trough 10 and the receptacle 21, the T 18 is connected to a conduit 33 (Figs. 4 and 6) provided with an elbow 34 to which one end of a short 10 piece of pipe 35 is secured. The other end of the pipe 35 is provided with a cap 36. Upon removing the cap 36 the pipe 35 is swung downwardly, the elbow 34 turning on the conduit 33, in order to drain the trough 10 and the receptacle 21.

20 Mounted to dip into the trough 10 are two non-contacting, longitudinally fluted, cylindrical work supporting and coating rolls 37 and 38 (Figs. 2, 6 and 9) arranged to project through the open top of the trough 10. The roll 37, 25 which is the first of these two rolls to engage the leading edge of the sole as it passes through the machine, is a solid metal roll. As shown in Fig. 2 the roll 37 is provided on its opposite ends with cylindrical portions 39 and 40, respectively, 30 of reduced diameter. The end portion 39 is journaled in a slot 41 (Fig. 3) formed in the side wall 13, and a gear 42 (Figs. 2 and 7) is secured to the free end of the portion 39. In this free end the portion 39 is provided with a conical 35 center which engages and rotates on a conical point 43 (Figs. 1, 2 and 3) projecting laterally from the inside face of a bracket 44 supported from the side wall 13. The end portion 40 of the roll 37 is also provided with a conical center 40 45 (Fig. 8) which engages and rotates on a conical point 46 formed on one end of a rod 47. The rod 47 is longitudinally movable in a split sleeve 48 secured to the side wall 14, and the sleeve 48 is provided with external threads which are engaged by internal threads on a hand-wheel 49. With this construction the hand-wheel 49 may be loosened to allow the split sleeve 48 to expand and thus release the rod 47 which may be then moved longitudinally in the sleeve 48 to withdraw 50 the point 46 from the center 45. The roll 37 and its associated gear may then be removed bodily from the trough 10.

The gear 42 meshes with a gear 50 (Figs. 2, 3 and 7) formed on a sleeve 51 which is rotatably mounted on the cylindrical end portion, projecting through and beyond the side wall 13 (Fig. 3), of a bar 52 extending between the side walls 13 and 14 centrally of the trough 10. The opposite end of the bar 52 is also cylindrical and is 60 mounted in the side wall 14. The structure of that portion of the bar 52 lying within the trough will be described hereinafter. The sleeve 51 is secured to a double grooved pulley 53 rotatably mounted on the projecting end of the bar 65 52, and for driving the pulley 53, the frame 12 is provided with an electric motor 54 on the armature shaft 55 of which a double grooved pulley 56 is secured. The pulleys 53 and 56 may be provided with two belts. It is preferred, however, 70 to use a single belt 57, the lower runs of which are crossed as indicated in Figs. 1, 2 and 3.

The roll 38 is built up on a spindle 58 (Fig. 5) the opposite ends of which are provided, respectively, with centers 59 and 60 in order that the 75 spindle 58 may be supported and removed readily

in the same manner as described previously in connection with the roll 37. Intermediate its ends the spindle 58 is provided with an hexagonal portion 61 which forms a core for a sponge-rubber body portion 62. The body portion 62 is interposed between two washers 63 and 64 mounted on a cylindrical portion of the spindle 58, and the washers are held in place by collars 65 and 66, respectively, secured to the spindle 58. The body portion 62 is covered by a synthetic rubber cover 10 67 provided on its coating applying surface with longitudinal flutes. The principal characteristic of the synthetic rubber is that it is compounded to resist any tendency of the latex to stick thereto.

15 The spindle 58 is provided with a gear 68 (Figs. 2, 5 and 7) which meshes with the gear 50. With this construction the two work supporting and coating rolls 37 and 38 are driven in the same counter-clockwise direction (viewing Fig. 6) 20 and at the same speed.

25 Cooperating with the lower work supporting and coating rolls 37 and 38 is a smooth-faced cylindrical upper roll 69 (Fig. 6) provided on its opposite ends, as shown in Fig. 3, with cylindrical portions 70 and 71, respectively, of reduced diameter. These reduced ends 70 and 71 engage and freely rotate on conical points 72 and 73, respectively, supported from an arm 74. The point 73 is formed on one end of a rod constructed and mounted as shown in Fig. 3 in the same manner as the rod 47 (Fig. 8), so that the roll 69 may be mounted or removed in the manner of the rolls 37 and 38.

30 The arm 74 is provided with a rear yoked end 75 (Fig. 1), a front yoked end 76, and a central curved bridge 77 (Figs. 1 and 6) overlying the upper roll 69 and forming a guard therefor. The rear yoked end 75 is provided with a pair of conical points 78 (Figs. 2, 3, 4, and 6) which engage, respectively, centers formed in the opposite sides of a yoked arm 79 (Figs. 1, 2, 3, 4, and 6) which is pivotally mounted on the rock-shaft 25 (Figs. 4 and 6). As indicated in Fig. 4, the arm 74 is adapted to be tipped upright, 45 swinging into this position on the conical points 78 engaged with the centers on the arm 79. But since the arm 79 is itself pivotally mounted on the rock-shaft 25, it is clear that the pivotal axis of the arm 74 on the arm 79 may be shifted. 50 Stated in another way, any movement of the arm 79 about its pivotal axis, formed by the rock-shaft 25, necessarily causes the centers on the arm 79, and therefore the conical points 78 and the arm 74, to move also. The purpose of 55 this construction will be described hereinafter, but it may be said that the pivotal axis of the arm 74 on the arm 79 may be maintained in a fixed position of adjustment during the operation of the machine by means of a thumb nut 80 (Figs. 4, 6 and 7) and an adjustable stop-screw 81 (Fig. 6). As best shown in Fig. 6 the thumb nut 80 is threaded on the end of a rod 82 projecting rearwardly from the trough 10 through a lug depending from the arm 79. The thumb nut 80 holds a washer in engagement with the lug on the arm 79 so that the swinging of the arm 79 to the left on the rock-shaft 25, viewing Fig. 6, may be limited as desired. The swinging of the arm 79 to the right from the position determined by the thumb nut 80 is prevented by the stop-screw 81 which, as shown in Fig. 6, is carried by the arm 79 and is adapted to abut the rear wall 16.

60 The upper roll 69 may be moved towards the 75

lower work supporting and coating rolls 37 and 38 under the influence of gravity. The approach movement of the roll 69 is limited definitely by the bottom ends of screws 83 and 84. (Figs. 1 and 2), which engage, respectively, the tops of the side walls 13 and 14. The screws 83 and 84 are threaded through the front yoked end 76 and are locked thereon in the desired position of adjustment by lock-nuts 85 (Fig. 7) and 86 (Fig. 4), respectively. During any shift of the pivotal axis of the arm 74 by reason of a re-adjustment by the operative of the thumb nut 80 and the stop-screw 81, the bottom ends of the screws 83 and 84 ride along the tops of the side walls 13 and 14, respectively.

The illustrated embodiment of the present invention operates upon short, flexible work pieces, such as shoe soles. In this class of work only one face is coated, and therefore it is essential that the upper roll 69 be kept free of coating in order to prevent soiling the uncoated face of the work. This desideratum is obtained, whether work is in the machine or not, by maintaining through the adjustment of the screws 83 and 84, 25 the periphery of the roll 69 spaced from the peripheries of the rolls 37 and 38 a distance at least greater than the thickness of the work.

In order to yieldingly resist the tendency of the shoe soles to elevate the roll 69 during their 30 passage through the machine, the side walls 13 and 14 are provided, respectively, with rotatable blocks 87 (Fig. 7) and 88 (Fig. 4) each provided with an opening which loosely receives a rod 89 threaded at its lower end upon a nut 90. Coiled 35 around each rod 89 is a spring 91 interposed between the nut 90 and a washer 92 loosely mounted on the rod beneath the block. The upper end of each rod 89 is provided with a thumb-piece 93. With this construction the rods 89 may be swung 40 into a position where the upper ends thereof are received, respectively, in slots 94 and 95 (Figs. 1 and 2) formed on the front yoked end 76 and against which the thumb pieces 93 rest in order 45 to hold the upper roll 69 yieldingly in operative position.

The illustrated embodiment of the present invention is employed in coating the flesh face of shoe soles of both the plain type and the shanked-out type. During the passage of a sole through 50 the machine the relative locations of the peripheries of the rolls 37, 38 and 69 cause the sole to bend and to be wrapped about the periphery of the roll 69 thus causing it to subject the sole to a tractive effort impelling it to the left, (Fig. 6), 55 notwithstanding the fact that the spaces between the periphery of the roll 69 and the peripheries of the respective rolls 37 and 38 are too great to allow the adjacent rolls to nip the work. With this construction and mode of operation the flesh 60 face of the sole is bent convexly about an axis extending at right angles to the length of the sole during the application of the coating thereto by the rolls 37 and 38. The bending of the flesh face of the sole in this manner opens up the pores 65 therein to allow the coating to penetrate into the body portion of the sole, thus providing for a strong bond. Owing to the tendency of the sole to resist the bending action, the flesh face of the sole is pressed firmly into engagement with the 70 surface of the rolls 37 and 38, thus causing them to drive the coating into the body portion of the sole through the opened pores in the convexly bent flesh face. The pressure exerted by the bent sole on the surface of the roll 38 causes the 75 synthetic rubber surface thereof to adapt itself

to the surface of the flesh face of the sole across its width, thus insuring the simultaneous application of coating to the planiform and non-planiform surfaces of a shanked-out sole.

In order to increase the tendency of the bent 5 sole to press itself firmly into engagement with the coating rolls 37 and 38, the arm 74 is provided with two small rotatably mounted cylindrical rolls 96 and 97 (Fig. 6), one of which, the roll 96, engages the leading edge of the sole first, 10 and the other one of which, the roll 97, engages the trailing edge of the sole last during the passage of the sole through the machine.

The rolls 96 and 97 are similar in construction. The opposite ends of the roll 96 are provided with 15 conical centers which rotate on conical points 91 and 92, respectively, (Fig. 2) removably mounted on a double-yoked arm 99 pivotally mounted on conical points 100 and 101 carried by the front yoked end 76 of the arm 74. The roll 96 is 20 adapted to be pressed yieldingly into engagement with the uncoated face of the sole. To this end the arm 99 is provided with a pair of ears 102 (Figs. 1, 2, and 6) which support a pivot pin 103. Loosely mounted on this pivot pin 103 between the ears 102 is a rod 104 having a thumb nut 105 threaded on its upper end. The rod 104 is received removably in a slot 106 (Fig. 2) formed on one upwardly bent end 107 of a plate 108 secured to the curved guard 77, the construction 30 being such that the bent end 107 of the plate 108 is interposed between the thumb nut 105 and a washer 109 loosely mounted on the rod 104. Coiled about the rod 104 and interposed between the washer 109 and a second washer 110 on the 35 rod 104 is a spring 111 which yieldingly resists any tendency of the sole to press the roll 96 upwardly and cause the arm 99 to swing on the conical points 100 and 101. The tension of the spring 111 and the position of the roll 96 may 40 be adjusted by means of the thumb nut 105.

The roll 97 is yieldingly mounted on the rear yoked end 75 of the arm 74 in a manner similar to the mounting of the roll 96 on the front yoked end 76, but the opposite end 112 of the plate 45 108 is longer than the end 107 and is not bent upwardly at so great an angle as the end 107. With this construction, when the rolls 96 and 97 are in operating position, the roll 97 is normally nearer the roll 38 than the roll 96 is near 50 the roll 37. The rolls 96 and 97, or either of them, may be thrown out of operation without removing the rods 104 from the slots 106, as shown in construction lines in Fig. 4, by swinging the arms 99 slightly upwardly and away from 55 the bridge 77.

The rolls 96 and 97 increase the tendency of the bent sole to press itself firmly into engagement with the coating rolls 37 and 38, but with thick soles, which give the greatest resistance to 60 the bending action, it is desirable that they be caused to press themselves very firmly into engagement with the synthetic rubber surface of the roll 38 to insure that the skived or non-planiform portions are completely coated. To this end 65 the pivotal mounting of the arm 74 upon the pivotally mounted arm 79 is provided, so that by adjusting the thumb nut 80 and the stop-screw 81, the pivotal axis of the arm 74 with the arm 79 may be shifted to bring the upper roll 69 70 nearer to the roll 38 than to the roll 37.

The reason for this construction lies in the nature of the bending of the sole by the upper roll 69 in its position spaced from the rolls 37 and 38 75 a distance at least greater than the thickness of

the work. With the roll 69 equally spaced in this manner from the rolls 37 and 38, the amount of sole flexion at the contact points of the sole with the rolls 37 and 38 will be equal. Stated in another way, the sole will press itself equally hard upon each of the rolls 37 and 38 because the amounts of flexion at those points are equal. If, however, the roll 69 is nearer to one of the lower rolls than it is to the other, the nearer together will be the contact point of the roll 69 with the grain face of the sole and the contact point of the lower roll in question with the flesh face of the sole, and the greater will be the flexion of the sole in the vicinity of the two rolls. The greater the flexion, the greater will be the pressure of the sole upon the lower roll. This is of practical importance in coating the skived portions of thick soles. The roll 38, being made of yielding material, is adapted to conform to the flesh face of the sole across its width, thereby coating the skived as well as the unskived portions thereof; but the thicker the sole, the harder must it press itself into the roll 38 to effect this coating and the greater will be the resistance both to flexion of the sole because of its thickness and to a depression of the material of the roll 38. The pressure of a sole of a given thickness on the roll 38 when the roll 69 is equally spaced from the rolls 37 and 38 may be just sufficient to cause a coating of the skived portions of the sole, but insufficient to cause a coating of the skived portions of a thicker sole. As a consequence, by adjusting the thumb nut 80 and the stop-screw 81, the arm 74 may be moved to the left, viewing Fig. 6, to cause the upper roll 69 to be located nearer to the roll 38 than to the roll 37, thereby insuring a proper coating of the skived portions of thick soles.

Viewing Fig. 6, it will be seen that in any swinging of the arm 74 upon the pivotal axis comprising the conical points 78, the roll 96 has a greater arcuate movement than do the rolls 69 and 97 and the roll 69 has a greater arcuate movement than does the roll 97. More particularly, the peripheral portions of the roll 69 which are adjacent the roll 37 have a greater arcuate movement than do the peripheral portions of the roll 69 which are adjacent the roll 38. It has been pointed out above that the downward swinging of the arm 74 is limited by the adjustable screws 83 and 84. With this construction and operation, it is apparent that with the thumb nut 80 and the stop-screw 81 so adjusted as to cause the roll 69 to be located centrally over the rolls 37 and 38, the screws 83 and 84 may be adjusted to cause a downward swinging of the arm 74 on its pivotal axis under the influence of gravity. This downward swinging, because of the above stated position of the roll 69, causes the peripheral portions of the roll 69 which are adjacent the roll 37 to approach closer to the roll 37 than the peripheral portions of the roll 69 which are adjacent the roll 38 approach the roll 38. Stated in another way, by reason of the adjustable screws 83 and 84 and the pivoting of the arm 74, the roll 69 may be moved to a position in which it is closer to the roll 37 than to the roll 38. It may be in this swinging of the arm 74 to position the roll 69 as just stated, that the rolls 96 and 97, or either of them, may become improperly positioned. If this result occurs, a repositioning of the rolls 96 and 97 is easily effected by adjusting the thumb nuts 105. Moreover, by manipulating the thumb nut 80 the roll 69 may be adjusted to a position in which it is closer to the roll 37 than to the roll 38. With

this construction and mode of operation the machine is adapted to operate upon work differing widely in thicknesses.

The soles are fed into the machine from a table 113 supported partially by extensions (Figs. 2 and 6) of the side walls 13 and 14 and partially by a post 114 (Fig. 4) secured to and projecting upwardly from the base 12.

In order that the soles may be coated properly, doctors for controlling the amount of coating material delivered to the work are associated with the up-going sides of the rolls 37 and 38, respectively. The up-going side of the roll 37 is associated with a doctor 115 (Fig. 6) comprising a plate (Fig. 3) secured to the front wall 15 and 15 provided with a rear straight edge spaced from the peripheral surface of the roll 37 about .0015 of an inch throughout its extent. In order to break up bubbles and to prevent strings of latex from being flicked upwardly into engagement 20 with the upper roll 69, the extensions of the side walls 13 and 14 support pivotally a plate 116 the rear edge of which is beveled to overlie closely the roll 37. The front edge of the plate 116 is provided with a tail 117 which carries an adjustable stop screw 118 (Fig. 6) arranged to engage the under surface of the table 113 and hold the beveled edge of the plate 116 in its desired position of adjustment. As shown in Fig. 6, the top surface of the plate 116 lies in a plane above the 30 uppermost element of the surface of the roll 37.

The up-going side of the roll 38 is associated with a doctor 119 (Figs. 6 and 9) comprising a flat plate having a straight edge 120 spaced closely from the peripheral surface of the roll 38 35 throughout its extent. The doctor 119 is adapted to be adjustably secured to the bar 52, and to this end the upper portion of the bar 52 is cut away to provide a flat surface 121 (Fig. 9) which is slightly longer than the doctor 119, as indicated 40 in Fig. 3. The doctor 119 is provided near its ends with a pair of slots 122 which embrace, respectively, the shanks of screws 123 for securing the doctor 119 to the surface 121 with the straight edge 120 in a desired position of nearness to the 45 roll 38. The doctor 119 is also provided near its ends with a second pair of slots 124 which embrace, respectively, posts 125 (Fig. 9) threaded into the bar 52 and rising vertically from the flat surface 121. Mounted on the posts 125 is a 50 straight edge 126 which serves to break up bubbles of latex and to prevent strings thereof from being flicked upwardly from the doctor 119 into engagement with the roll 69 in the same manner that the beveled edge of the plate 116 performs 55 these functions in connection with the roll 37 and its doctor 115.

In operating the machine to coat the flesh faces of soles, the operative with her right hand places a sole flesh face down upon the table 113 60 and pushes it through the space between the plate 116 and the roll 96 so that the leading edge of the sole passes across and over the roll 37 into engagement with the roll 69. The sole is pushed hard enough so that it commences to bend downwardly in engagement with the roll 69, and since the roll 37 is driven, as soon as the leading edge of the sole begins its downward bending, traction is produced on the sole by the rolls 69 and 37 to cause a feeding of the sole without further act 65 by the operative. After being initially bent by the roll 69, the leading edge of the sole traverses the space between the rolls 37 and 38 until the leading edge strikes the upgoing side of the roll 38, which causes an upward bending of the lead- 75

ing edge of the sole, thereby in turn causing the grain face of the sole to be wrapped around a portion of the periphery of the roll 69 and causing the flesh face of the sole to press against the rolls 37 and 38 at points spaced from the wrapped portion. In this position the flesh face of the sole is bent convexly about an axis extending at right angles to the length of the sole. As the leading edge of the sole continues in its passage through the machine it next tends to pass upward into the space between the rolls 69 and 97.

In order to prevent the turned-up leading edge of the sole from passing upward into the space between the rolls 69 and 97, the bridge 11 supports along its rear edge portion (Figs. 1 and 6) a guard 127. This guard comprises a plate the body of which conforms to the curvature of the bridge 11 and the lower portion 128 of which is bent radially towards the roll 69 and terminates near it. As shown in Fig. 6, the radial portion 128 is located below the axis of the roll 69 with the result that the radial portion 128 is inclined rearwardly downwardly, or to the left, viewing Fig. 6. With this construction, the turned-up leading edge of the sole, in striking the radial portion 128, is bent downwardly and so passes under the roll 97.

When the leading edge of the sole is bent downwardly under the roll 97, the flesh face of the sole is wrapped around a portion of the periphery of the roll 38. The feed of the sole continues, the trailing edge of the flesh face of the sole successively passing over the table 113, the plate 116, the roll 37 and the roll 38. As soon as the trailing edge clears the space between the rolls 37 and 38, the leading edge of the sole has been projected out of the space between the peripheries of the rolls 38 and 97 far enough for the operative to grasp with her hand the leading edge of the sole, which extends conveniently downwardly because of the bending imparted by the roll 97, after which the sole passes out of the machine.

From the foregoing it will be seen that in spite of the fact that the upper roll 69 is spaced from the peripheries of the lower rolls 37 and 38 a distance at least greater than the thickness of the work, there is sufficient traction to feed the sole through the machine so long as the sole is bent in engagement with the rolls 37 and 69, or 37, 69, and 38, or 37, 69, 38 and 97, and also, during further passage of the sole through the machine, when bent in engagement with the rolls 69, 38, and 97. During the feed of the sole the function of the roll 96 is to maintain the trailing portion of the sole substantially flat over the table 113 to cause a greater flexion over the roll 37 than would be the case without the roll 96.

It has been pointed out above that when the sole engages the upper roll 69 and the lower rolls 37 and 38, the flesh face of the sole is bent convexly about an axis extending at right angles to the length of the sole during the application of the coating thereto by the rolls 37 and 38. By reason of the guard 127 and the roll 97, however, after the flesh face of the sole has been bent as just stated, it is then bent concavely about an axis extending at right angles to the length of the sole during the application of coating by the rolls 37 and 38. With this construction the sole is first bent convexly, as stated, then simultaneously convexly at one portion and concavely at another, and finally concavely. It will be apparent that during these bendings of the sole in its passage through the machine, the rolls 37, 69, and

38 first cooperate in the feed of the sole, then the rolls 37, 69, 38 and 97 cooperate, and then finally the rolls 69, 38 and 97 cooperate.

Nothing herein explained is to be interpreted as limiting the various features of the present invention in the scope of its application to use in connection with the particular machine or the particular mode of operation or any combination thereof selected for purposes of illustration and explanation. While the particulars of construction herein set forth are well suited to one mechanical form of the invention and to the uses to which it is put, it is not limited as to these uses, nor to these details of construction, nor to the conjoint use of all its features, nor is it to be understood that these particulars are essential since they may be modified within the skill of the artisan without departing from the true scope of the actual invention, characterizing features of which are set forth in the following claims by the intentional use of generic terms and expressions inclusive of various modifications.

What is claimed as new, is:

1. In a cementing machine, the combination with a pair of lower work supporting rolls, at least one of said rolls applying coating to one face of the work, an upper roll cooperating therewith during the feed of the work, and means for holding the upper roll operatively spaced from the lower rolls a distance at least greater than the thickness of the work, of means for positioning the upper roll in said operatively spaced relation closer to one of the lower rolls than to the other.

2. In a sole cementing machine, the combination with a pair of lower work supporting rolls, at least one of said rolls applying coating to one face of the work, one of said rolls engaging the leading edge of the sole first and the other one of said rolls engaging the trailing edge of the sole last, an upper roll cooperating with the lower rolls during the feed of the sole and means for holding the upper roll operatively spaced from the lower rolls a distance at least greater than the thickness of the sole, of means for positioning the upper roll in said operatively spaced relation closer to the lower roll which engages the leading edge of the sole first than to the other lower roll.

3. In a sole cementing machine, the combination with a pair of lower work supporting rolls, at least one of said rolls applying coating to one face of the work, one of said rolls engaging the leading edge of the sole first and the other one of said rolls engaging the trailing edge of the sole last, an upper roll cooperating with the lower rolls during the feed of the sole, and means for holding the upper roll operatively spaced from the lower rolls a distance at least greater than the thickness of the sole, of means for positioning the upper roll in said operatively spaced relation closer to the lower roll which engages the trailing edge of the sole last than to the other lower roll.

4. In a cementing machine, the combination with a pair of lower work supporting rolls, at least one of which applies coating to one face of the work, a pivoted arm, an upper roll carried thereby engaged with the uncoated face of the work and cooperating with the lower rolls in the feed of the work, and means for holding the upper roll in an operating position spaced from the lower rolls a distance at least greater than the thickness of the work, of means for relatively shifting the pivotal axis of the arm and the lower rolls.

5. In a cementing machine, the combination with a frame, a pair of lower work supporting

- rolls, at least one of which applies coating to one face of the work, an upper roll cooperating therewith during the feed of the work, a pivoted arm for supporting the upper roll, resilient means interposed between the frame and the arm tending to force the upper roll towards the lower rolls, and means for holding the upper roll in an operating position spaced from the lower rolls a distance at least greater than the thickness of the work, of means for relatively shifting the pivotal axis of the arm and the lower rolls.
6. In a cementing machine, the combination with a pair of lower work supporting rolls, at least one of which applies coating to one face of the work, an arm pivoted on an axis in the rear of the axes of said rolls, and a second arm pivoted on the first arm, of an upper roll carried by the second arm engaged with the uncoated face of the work and cooperating with the lower rolls in the feed of the work.
7. In a cementing machine, the combination with a pair of lower work supporting rolls, at least one of which applies coating to one face of the work, an arm pivoted on an axis in the rear of the axes of said rolls, and a second arm pivoted on the first arm on an axis in the rear of the axes of said rolls, of an upper roll carried by the second arm engaged with the uncoated face of the work and cooperating with the lower rolls in the feed of the work.
8. In a cementing machine, the combination with a pair of lower work supporting rolls, at least one of which applies coating to one face of the work, an arm pivoted on an axis in the rear of the axes of said rolls, a second arm pivoted on the first arm, and an upper roll carried by the second arm engaged with the uncoated face of the work and cooperating with the lower rolls in the feed of the work, of means for adjusting the pivotal axis between the first and second arms to any one of a plurality of positions and for maintaining said pivotal axis in said position of adjustment.
9. In a cementing machine, the combination with a pair of lower work supporting rolls, at least one of which applies coating to one face of the work, an arm pivoted on an axis in the rear of the axes of said rolls, a second arm pivoted on the first arm, an upper roll carried by the second arm engaged with the uncoated face of the work and cooperating with the lower rolls in the feed of the work, and means for adjusting the pivotal axis of the second arm with the first arm to any one of a plurality of positions and for maintaining said pivotal axis in said position of adjustment, of means for moving the axis of the upper roll relatively to the axes of the lower rolls while maintaining said fixed position of adjustment of the pivotal axis of the second arm with the first arm.
10. In a cementing machine, the combination with a pair of lower work supporting rolls, at least one of which applies coating to one face of the work, a pivoted arm, an upper roll carried thereby engaged with the uncoated face of the work and cooperating with the lower rolls in the feed of the work, and means for holding the upper roll in an operating position spaced from the lower rolls a distance at least greater than the thickness of the work, of at least one auxiliary roll smaller than the upper roll mounted upon the pivoted arm and cooperating with the upper roll and one of the lower rolls in the feed of the work.
11. In a cementing machine, the combination with a pair of lower work supporting rolls, at least one of which applies coating to one face of the work, a pivoted arm, an upper roll carried thereby engaged with the uncoated face of the work and cooperating with the lower rolls in the feed of the work, and means for holding the upper roll in an operating position spaced from the lower rolls a distance at least greater than the thickness of the work, of at least one auxiliary roll smaller than the upper roll pivotally mounted upon the pivoted arm and cooperating with the upper roll and one of the lower rolls in the feed of the work.
12. In a cementing machine, the combination with a frame, a pair of lower work supporting rolls, at least one of which applies coating to one face of the work, an arm pivoted to the frame, a second arm pivoted to the first arm, and an upper roll carried by the second arm engaged with the uncoated face of the work and cooperating with the lower rolls in the feed of the work, of at least one auxiliary roll mounted upon the second arm cooperating with the upper roll and one of the lower rolls during the feed of the work.
13. In a cementing machine, the combination with a pair of lower work supporting rolls, at least one of which applies coating to one face of the work, an arm pivoted on an axis in the rear of the axes of said rolls, a second arm pivoted on the first arm, an upper roll carried by the second arm engaged with the uncoated face of the work and cooperating with the lower rolls in the feed of the work, at least one third arm pivotally mounted on the second arm, an auxiliary roll mounted on said third arm, and means for adjusting the pivotal axis between the first and second arms to any one of a plurality of positions and for maintaining said pivotal axis in said position of adjustment, of means permitting a swinging of the third arm on the second arm while the pivotal axis between the first and second arms is maintained adjusted.
14. In a cementing machine, the combination with a pair of lower work supporting rolls, at least one of which applies coating to one face of the work, a pivoted arm, an upper roll carried thereby engaged with the uncoated face of the work and cooperating with the lower rolls in the feed of the work, and means for holding the upper roll in an operating position spaced from the lower rolls a distance at least greater than the thickness of the work, of two auxiliary rolls pivotally mounted, respectively, upon the pivoted arm, one of said auxiliary rolls cooperating with the upper roll and one of said lower rolls in the feed of the work and the other of said auxiliary rolls cooperating with the upper roll and the other of said lower rolls in the feed of the work.
15. In a cementing machine, the combination with a pair of lower work supporting rolls, at least one of which applies coating to one face of the work, a pivoted arm, a second arm pivoted on the first arm, an upper roll carried by the second arm engaged with the uncoated face of the work and cooperating with the lower rolls in the feed of the work, two auxiliary rolls pivotally mounted, respectively, upon the second arm, one of said auxiliary rolls cooperating with the upper roll and one of said lower rolls in the feed of the work and the other of said auxiliary rolls cooperating with the upper roll and the other of said lower rolls in the feed of the work, and means for adjusting the pivotal axis between the first and second arms.

- the first and second arms to any one of a plurality of positions and for maintaining said pivotal axis in said position of adjustment, of means operatively connected, respectively, to the second arm and to the auxiliary rolls for permitting movements of the axes of said auxiliary rolls independently of each other during the feed of the work while the pivotal axis between the first and second arms is maintained adjusted.
- 5 16. In a cementing machine, the combination with a frame, a trough therein for the coating, and a receptacle, for a source of coating supply having an outlet connected to the trough and located thereabove during the operation of the machine, of means for lowering the receptacle to locate its outlet below the trough, including a rock-shaft journaled on the frame, an arm carried by the rock-shaft and pivotally connected to the receptacle, a link pivotally connected to both 10 the frame and the receptacle, and an arm for rocking the rock-shaft.
- 10 17. In a cementing machine, the combination with a frame, a trough therein for the coating, and a receptacle, for a source of coating supply, having an outlet connected to the trough and located thereabove during the operation of the machine, of means for lowering the receptacle to locate its outlet below the trough, including a rock-shaft journaled on the frame, an arm carried by the rock-shaft and pivotally connected to the receptacle, a link pivotally connected to both 15 the frame and the receptacle, an arm for rocking the rock-shaft, and means for preventing the rock-shaft from rocking.
- 20 18. In a cementing machine, the combination with a roll having on at least one end thereof a reduced cylindrical portion, of means for supporting at least the cylindrical portion comprising a stationary split sleeve provided with external threads, a rod longitudinally movable in the sleeve, said rod having a conical point upon which the said cylindrical portion rotates, and a handwheel having internal threads engaged with the external threads on the sleeve for clamping the sleeve on the rod.
- 25 19. A cementing machine having, in combination, a trough for containing coating material, a coating roll rotatable in the trough, a support mounted in the trough, a doctor secured to the support and provided with a scraping edge located closely adjacent the up-going side of the coating rolls, posts extending upwardly from the support, and a splash guard mounted on the posts for breaking up bubbles of the coating material and for preventing an upward flicking of coating 30 material above the roll by the doctor.
- 30 20. A cementing machine having, in combination, a trough for containing coating material, a coating roll rotatable in the trough, a support mounted in the trough, posts extending upwardly from the support, a doctor comprising a plate adjustably secured to the support and provided with slots embracing the posts and with a scraping edge located closely adjacent the up-going side of the coating roll, and a splash guard 35 mounted on the posts above the doctor for breaking up bubbles of coating material and for preventing an upward flicking of coating material above the roll by the doctor.

WALTER P. OSGOOD. 35
